(57) **CLAIM**

The ornamental design for a nipple for nursing bottle, as shown and described.

DESCRIPTION

FIG. 1 is a top, front perspective view of nipple for nursing bottle, showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

(Continued)

FIG. 8 is a cross-sectional elevation view of the nipple for nursing bottle, taken in the direction of line 8-8 of FIG. 6.
